UNITED STATES PATENT OFFICE.

RICHARD E. BROCK AND WILLIAM M. SELKIRK, OF MONESSEN, PENNSYLVANIA, ASSIGNEES TO PITTSBURGH STEEL PRODUCTS COMPANY, OF PITTSBURGH, PENNSYLVANIA, A CORPORATION OF PENNSYLVANIA.

TUBE-ROLLING APPARATUS.

1,020,399.

Specification of Letters Patent. Patented Mar. 19, 1912.

Application filed December 30, 1910. Serial No. 800,081.

To all whom it may concern:

Be it known that we, RICHARD E. BROCK and WILLIAM M. SELKIRK, residents of Monessen, in the county of Westmoreland and State of Pennsylvania, have invented a new and useful Improvement in Tube-Rolling Apparatus; and we do hereby declare the following to be a full, clear, and exact description thereof.

10 Our invention relates to tube rolling apparatus and more especially to the rolling of seamless tubing.

The object of our invention is to provide a simple and efficient form of mechanism by 15 means of which the tube-blank when forced through the roll-pass onto the mandrel may be stripped from the mandrel and returned to the receiving side of the rolls without the necessity of raising the rolls or passing the 20 blank over or under the same.

To these ends our invention consists, generally stated, in a two-high mill having a pass for the tube in rolling and a dummy-pass, means for feeding the tube-blank onto 25 the mandrel bar supported in the roll-pass, and means for withdrawing the mandrel-bar and the tube thereon and moving the tube and mandrel-bar transversely in line with the dummy-pass, and means for feeding the 30 tube back through the dummy-pass to the receiving side of the rolls to be again brought into alignment with the working-pass, and the mandrel therein for another passage through the rolls.

35 In the drawings Figure 1 is a plan view of our improved apparatus, showing the mandrel and tube blank after the tube has been forced onto the mandrel; Fig. 2 is a like view showing the mandrel and tube in position with reference to the dummy-pass; Fig. 3 is a side elevation partly in section; Fig. 4 is an end view; and Fig. 5 is a cross-section on the line 5—5 Fig. 1 with mandrel bar support partly broken away.

40 In the drawings the numeral 2 designates a suitable housing, containing the rolls 3, driven in opposite directions by any suitable power. These rolls have the working-passes 4 and the dummy-pass 5.

50 At the receiving side of the rolls is the table or trough 6 which is mounted on the supports 7 and is laterally movable thereon by means of the cylinders 8. A pusher 9 is provided at the receiving side of the rolls

which is operated by means of the cylinder 55 10. At the opposite side of the rolls is the mandrel-support 11 which consists of the bars 12 which are supported at their forward ends by the housing and at their rear ends in the back-stop 13, said bars passing 60 through said back-stop and having the nuts 14 secured thereto. A movable back-stop 15 is mounted to slide upon the rods 12 and interposed between said movable back-stop 15 and the back-stop 13 is the removable 65 spacer or block 16. The movable back-stop 15 is moved by means of the cylinder 17, the piston rod 18 of which is connected to said back-stop. To raise and lower the removable block 16 we employ a cylinder 19. 70 The sides of the block 16 are preferably slightly tapered as indicated and engage the tapering faces 20 and 21 of the back-stops 15 and 13 for the purpose more fully hereinafter set forth.

75 The mandrel-bar supports 22 are arranged at intervals on the rods 12 and movable in said supports are the guides 23. These guides 23 are provided with the flaring mouthed passages 24 for the reception of 80 the mandrels and the tubular-blank surrounding the same. The guides 23 have a dove-tail connection with the supports 22. Pitmen 25 are connected to the guides 23 and at their opposite ends said pitmen are 85 connected to the straps 26 of the eccentrics 27. The eccentrics 27 are keyed to the shaft 29 and said shaft is supported by the arms 30 extending from one of the rods 12. At one end of the shaft 29 is the pinion 31^a 90 which is engaged by the rack 31. This rack 31 is connected up to the cylinder 32.

The key 33 on the shaft 29 engages a key-way on the eccentric 27^a adjacent to the movable back-stop 15 and connected thereto to 95 provide for the sliding of the eccentric on the shaft 29, when the back-stop 15 is moved backward and forward. An anchor-bar 34 is dove-tailed to slide in the back-stop 15 and said anchor-bar forms the support for 100 the rear end of the mandrel-bar 35. The mandrel-bar may be screwed or otherwise secured in said anchor-bar. This anchor-bar is connected by the pitman 36 to the strap of the eccentric 27^a connected to the 105 movable back-stop 15.

In the operation of our improved apparatus, in the rolling of tubes, the tubular-

2

blank 40 is placed in the trough 6 in line with the working-pass 4 of the rolls. The blank is forced into the rolls by means of the pusher 9 and is carried by the action of the rolls over the mandrel-plug and onto the mandrel-bar 35. When the tubular blank has passed completely through the rolls it is necessary to provide for transferring the tubular-blank over the mandrel-bar to the opposite or receiving side of the rolls to be again passed through the same. This we accomplish in the following manner: The block 16 is lowered by admitting fluid to the cylinder 19 and when said block is lowered the movable back-stop 15 is moved back by admitting fluid to the cylinder 17. The tapering of the block 16 prevents the binding of said block and permits of its being withdrawn and moved into engagement with the back-stop more readily. By the backward movement of the back-stop 15 the mandrel-bar 35 connected to the anchor-bar 34 is moved backward until the forward end of the mandrel the mandrel-plug having been removed, clears the rolls as indicated in Fig. 2. Motive fluid is now admitted to the cylinder 32 and through the rack-bar 31 and pinion 31^a a rotary movement is imparted to the shaft 29. The eccentric are rotated and through the action of the pitmen 25 the guides 23 are moved in the supports 22 and the mandrel-bar together with the tube are moved over into the position indicated in Fig. 2 in line with the dummy-pass 5. With the tubular-blank in line with the dummy-pass the blank is forced through said dummy-pass and stripped from the mandrel-bar 35 until it is transferred to the receiving trough 6 at the other side of the rolls. This stripping of the tubular-blank from the mandrel-bar 35 and the carrying of it through the dummy-pass may be accomplished by means of suitable feed rolls 37 which are operated by means of cylinders 38. The tubular blank may be pushed by any suitable means into position to be seized by the rolls 37. The trough 6 is now moved over into line with the working-pass of the rolls by means of the cylinders 8 and at the same time the rack-bar 31 is moved in the opposite direction and the shaft 29 rotated to move the mandrel-bar and its support back into position in line with the working-pass to receive the tubular-blank as it is again fed to the rolls by the pusher 9. In this manner we provide for the transfer of the tubular blank to the receiving side of the rolls without passing the same over or below the rolls and without lifting the rolls, the operation of withdrawing the mandrel-bar and moving it laterally being accomplished with great rapidity so that there is little opportunity for the blank to cool in the transfer back to the receiving side of the rolls.

What we claim is:

1. In apparatus for rolling tubing, the combination of power-driven rolls having a working-pass and a dummy-pass, a mandrel-bar to receive the tube, means for withdrawing the mandrel-bar, and means for moving the mandrel-bar and the tubular-blank carried thereby transversely into line with the dummy-pass. 70

2. In apparatus for rolling tubing, the combination of power-driven rolls having a working-pass and a dummy-pass, a mandrel-bar supported in line with the working-pass, and means for successively withdrawing said mandrel-bar and moving the same transversely together with the tubular-blank supported thereby into line with the dummy-pass. 80

3. In apparatus for rolling tubing, the combination of power-driven rolls having a working-pass and a dummy-pass, a mandrel-bar, a movable back-stop for said mandrel-bar, a transversely movable support for said mandrel-bar, and mechanism for moving said transversely movable support to bring said mandrel-bar and the tubular-blank supported thereby into line with the dummy-pass. 85

4. In tube rolling apparatus, the combination of power-driven rolls having a working-pass and a dummy-pass, a mandrel bar, a movable back-stop for said mandrel-bar, a transversely movable anchor on said back-stop with which said mandrel-bar engages, and mechanism for moving said anchor to bring said mandrel-bar and the tubular-blank supported thereby into line with the dummy-pass. 95

5. In apparatus for rolling tubing, the combination with power-driven rolls having a working-pass and a dummy-pass, a mandrel-bar, a movable back-stop, a transversely movable anchor on said back-stop with which said mandrel-bar engages, transversely movable mandrel-bar supports at intervals, and mechanism for moving said anchor-bar and supports simultaneously to bring said mandrel-bar and tubular-blank carried thereby into line with the dummy-pass. 105 110

6. In apparatus for rolling tubing, the combination of power-driven rolls having a working-pass and a dummy-pass, a mandrel-bar, a back-stop, a movable back-stop, a removable spacing member between said back-stops, said mandrel-bar being supported by said movable back-stop, and means for moving said mandrel-bar transversely to bring said mandrel-bar and the tubular-blank carried thereby into line with the dummy-pass. 115 120

7. In apparatus for rolling tubing, the combination of power-driven rolls having a working-pass and a dummy-pass, a mandrel-rod, a back-stop, a movable back-stop, 125 130

a tapering spacing member between said back-stops, said mandrel-bar being supported by said movable back-stop, and means for moving said mandrel laterally to bring said mandrel and the tubular-blank carried thereby into line with the dummy-pass.

8. In apparatus for rolling tubing, the combination of rolls having a working-pass and a dummy-pass, a mandrel-bar, a movable back-stop, transversely movable supports for said mandrel-bar, eccentrics, con-

nections between said eccentrics and said supports, and mechanism for operating said eccentrics.

In testimony whereof, we the said RICHARD E. BROCK and WILLIAM M. SELKIRK have hereunto set our hands.

RICHARD E. BROCK.
WILLIAM M. SELKIRK.
